(57) CLAIM

I claim the ornamental design for a wing-shaped rally towel, as shown and described.

DESCRIPTION

FIG. 1 is a front plan view of a wing shaped rally towel showing my new design;

FIG. 2 is a rear plan view thereof;

FIG. 3 is a second front plan view thereof;

FIG. 4 is a second rear plan view thereof;

FIG. 5 is a third front plan view thereof; and,

FIG. 6 is a third rear plan view thereof.

The dash broken line withing FIGS. 3-6 depict ways to hold the wing-shaped rally towel that are not included in the claim. The dash broken line shows environment and forms no part of the claimed design.
